UNITED STATES PATENT OFFICE.

WILLIAM H. BETTS, OF PORTLAND, OREGON.

SCREEN GASKET.

1,422,916.

Specification of Letters Patent. Patented July 18, 1922.

Application filed March 19, 1921. Serial No. 453,569.

To all whom it may concern:

Be it hereby known that I, WILLIAM H. BETTS, a citizen of the United States, and a resident of Portland, in the county of Multnomah and State of Oregon, have invented a new and useful Screen Gasket, of which the following is a specification.

This invention relates more particularly to gaskets such as are used between the carbureter and intake manifold of an internal combustion engine.

The object of my invention is to provide an exceedingly simple, inexpensive and efficient means for breaking up heavier oils such as kerosene, etc.

I attain these results in the manner set forth in the following specification and illustrated in the accompanying drawing in which:—

20 Figure 1 is an elevation of my device showing its relation to a carbureter and intake manifold. Figure 3 is a bottom view of the device. Figure 2 is a front elevation of the device. Figure 4 is a section along the line 4—4 in Fig. 3. Figure 5 is a top view showing one of the screens and part of the gasket removed. Figure 6 is an enlarged detail showing how the various elements are assembled.

30 Similar numbers of reference refer to the same or similar parts throughout the several views.

Referring in detail to the drawing, I have constructed my device of two layers of backing material 7 and 8 cut into the form of a manifold flange. Before placing the parts 7 and 8 together a piece of screen wire 9 is placed over the opening 10 in the gasket. Across this is placed a bridge 10^A, preferably 40 of sheet metal, whose ends are curled downwardly and under the ends of the screen 9 and secured thereto. At the center of this bridge 10^A is mounted a fan shaped disk 11 on the screw 12 which is secured to the 45 bridge 10^A by means of the nuts 13 above and below the bridge.

A bulging screen 14 is now placed over the

screen 9 and the portion 7 of the gasket put in place over the portion 8 to which it is now secured by means of a suitable cement, or in 50 any other convenient manner.

The operation of my device is as follows: It is installed by placing same as shown in Fig. 1 between the carbureter 15 and the intake manifold 16 with the bulging screen 55 14 toward the intake manifold. It will be seen that the majority of the fuel reaching the screen 9 strikes it near its center at which is located the fan 11. By bulging the screen 14, a spreading and spraying action 60 is secured which is so essential to the proper combustion of kerosene fuel.

I have found by experience that a thirty mesh screen best meets the requirements of this device as a finer screen will tend to 65 clog with fuel and retard the passage from the carbureter, whereas a coarser screen will not break up the articles sufficiently for the purpose intended.

I am enabled by the use of this device to 70 run a car of the Ford type with a standard carbureter entirely upon kerosene, using gasoline as a primer only at low temperatures.

I am aware that numerous single screen 75 gaskets have been tried with varying degrees of success, I therefore do not claim the use of the screen broadly but only in the manner set forth in the following claim.

What I claim as new is:—

80 A gasket adapted to be placed between the carbureter and the intake manifold flange of an internal combustion engine, consisting of two thicknesses of backing material of the same general shape and perforations as are 85 the flanges and having secured between same a flat screen facing the carbureter and a bulging screen facing the manifold, and having mounted across the center of said screens a bridge member, and a rotatable 90 fan mounted on said bridge between said screens.

WILLIAM H. BETTS.
